UNITED STATES PATENT OFFICE.

FRANCIS W. FERGUSON, OF LOUISVILLE, KENTUCKY.

CHIMNEY-TOP.

Specification of Letters Patent. Patented Mar. 31, 1914.

1,091,883.

Original application filed March 19, 1912, Serial No. 684,876. Divided and this application filed August 22, 1912. Serial No. 716,486.

To all whom it may concern:

Be it known that I, FRANCIS W. FERGUSON, a citizen of the United States, residing at Louisville, in the county of Jefferson and 5 State of Kentucky, have invented certain new and useful Improvements in Chimney-Tops; and I do hereby declare the following to be a full, clear, and exact description of the invention, such as will enable others 10 skilled in the art to which it appertains to make and use the same.

This invention relates to chimneys and especially to the top or discharge ends thereof.

The principal object of the invention 15 disclosed in this application, which is a division of my pending application Ser. No. 684,876, filed March 19, 1912, is to protect the masonry at the top of the chimney from having the mortar washed out and from 20 being discolored by dirty water running down the outside of the chimney.

Another object is to prevent rain or snow from passing down the flue of the chimney, so that said flue may be left open for ventilation 25 when the fires are out, as during the summer season, without danger of rusting out the metal pipes ordinarily used for connecting furnaces and stoves to the flue. It is common practice to take down these connecting pipes in the summer time where the flue is not protected from rain. The time and trouble incident to this practice is obviated when the present invention is used 30 on the chimney.

35 The invention will hereinafter be first fully described with reference to the accompanying drawings, which form a part of this specification, and then pointed out in the claims following the description.

40 In the drawings: Figure 1 is a side elevation of a brick chimney equipped with this invention. Fig. 2 is a transverse vertical section thereof. Fig. 3 is a top plan view of the same. Fig. 4 is a horizontal section 45 taken through the openings in the sides of the cap. Fig. 5 is a section taken on the line 5—5 of Fig. 2. Fig. 6 is a broken vertical section on the line 6—6 of Fig. 4. Fig. 7 is a broken vertical section of a modified 50 construction, and Fig. 8 is a broken horizontal section of another modification.

Referring to the drawings by letters of reference, A designates the upper part or end of the usual rectangular brick chimney 55 having a flue a. The improved top may be

placed directly upon the brick work, thereby dispensing with the cap-stone ordinarily used. Thus, the top may be placed upon the chimney as the last step in its construction, as shown, and may consist of a guard-plate or frame B, a cap C and a wind-shield D. The guard-plate is preferably formed 60 with a short tubular section b extending downwardly from its inner edge and fitting around the cap C. The lower end of this 65 tubular section rests upon the top layer of bricks of the chimney. The guard-plate slopes downwardly and outwardly from the upper end of said tubular section and also rests upon the top layer of bricks at the 70 outer edge of the same. Said guard-plate projects beyond the sides of the chimney proper, as at b¹, and preferably has its margin curved downwardly and terminating in a bead b².

The cap C may consist of a tubular section, the lower end of which fits into the upper end of the flue a. The upper end of 75 said tubular section is closed, as at c, preferably by a dome-shaped cover made integral therewith. Intermediate of its ends 80 said tubular section of the cap may be provided with an outwardly and downwardly extending flange c¹ which overlaps the guard-plate for preventing water from entering 85 between the tubular section b of said guard-plate and the tubular section of the cap.

The wind-shield D may be in the form of 90 a vertical wall inclosing a rectangular space, including the upper portion of the cap, and arranged in alignment with the outer surfaces of the walls of the chimney so as to conform to the shape of the latter. Said wind-shield 95 preferably rests upon the guard-plate and terminates at its upper end substantially on a level with the top of the cap. In the preferred form, the wind-shield is made integral with the cap, being connected thereto by vertical partitions or 100 wings d preferably arranged at the four corners. These partitions or wings serve to divide the space between the wind-shield and cap into four compartments d¹. Openings d² are provided at or near the lower 105 edge of the wind-shield, out of horizontal alignment with and preferably below openings c² in the sides of the tubular section of the cap.

When the top is to be placed upon the 110

chimney, the guard-plate is first laid on top of the masonry with its tubular section b registering with the flue opening. The combined cap and wind-shield is then adjusted 5 by inserting the lower portion c^2 of the cap through said tubular section of the guard-plate and down into the flue until the lower edge of the wind-shield and the flange c^1 come in contact with said guard-plate, as 10 shown in Fig. 2. It is desirable to place a thin layer or filling of cement E between the flange and plate, between the tubular section of said plate and the portion of the cap arranged within the same, and also between 15 the inner wall of the flue and the part of the cap which extends into said flue. This filling of cement binds the cap securely to the chimney, and as long as said cap remains in place, it will retain the guard-plate in proper position.

As illustrated at d^2 in Fig. 2, the compartments d^1 , which may be considered as outer flues, are open at the top to permit the escape 20 of the products of combustion which enter said compartments from the flue a through the openings c^2 in the cap. This discharge of the products of combustion is accelerated by the wind or air circulating in through 25 the openings d^2 in the wind-shield. The incline of the guard-plate aids by giving an upward lift to this wind or air. Said openings d^2 also serve as drains for the compartments, preventing the collection of water 30 therein which would tend to rust out the device if the same is made of metal. It is 35 preferable, however, to construct the device of reinforced material, such as cement, concrete or clay. The outer surface of the wind-shield may be colored and marked to 40 conform to the brick or stone work of the chimney, as shown in Fig. 1, whereby the device is not only pleasing in appearance, but practically indiscernible as a separate part from the chimney itself.

45 Should the wind or air currents which enter one or two of the compartments in the wind-shield interfere in any way with the smoke being discharged through said compartments, the other two compartments, 50 which are not subjected to the direct influence of the wind, are ample to carry off all of the products of combustion from the flue by reason of the fact that the cross-sectional area of any two adjacent compartments 55 is about equal to or greater than that of the flue or cap. That part of the wind which strikes the attachment and does not pass in through one or more of the openings in the wind-shield, is turned sharply upward 60 by the flat outer surfaces of the wind-shield and, as said wind passes above and beyond the open ends of the compartments, it further increases the draft by tending to create a vacuum in said compartments. This in-

fluence of the wind which passes upward on 65 the outside of the wind-shield is sufficient to counteract any tendency of the wind which enters said wind-shield to cause down-drafts in the flue.

Instead of constructing the guard-plate in 70 a separate piece, as hereinbefore described and illustrated in Figs. 1 to 6, inclusive, said plate may be made integral with the cap as shown in Fig. 7, thereby dispensing with the flange c^1 . It will also be observed that the 75 wind-shield and partitions d may be made in a separate piece from the cap, if desired, as shown in Fig. 8.

It is obvious that when it rains or snows, 80 water will enter the compartments of the wind-shield through their open upper ends and be discharged from the outer edges of the guard-plate well beyond the sides of the chimney by reason of the projecting portion b^1 of said plate. There is, consequently, no 85 danger of water reaching and washing out the mortar at the top of the masonry of the chimney, or of dirty or sooty water from the interior of the wind-shield running down the sides of the chimney and marring its 90 appearance. The cover of the cap, of course, excludes rain or snow from the flue, thus making it unnecessary to take down connecting pipes from furnaces or stoves to prevent said pipes from rusting out when 95 the fires are out, as already explained.

Having thus described my invention, what I claim as new and desire to secure by Letters Patent is:—

1. A chimney top comprising a cap, a 100 guard plate the outer edge of which terminates beyond and is free from the outer surface of the chimney proper, and the inner edge of which terminates in a downwardly extending tubular section fitting around the 105 cap for holding the plate rigidly in position, the lower edge of said tubular section resting upon the top of the chimney proper.

2. A chimney top comprising a cap, a 110 guard plate inclined outwardly and downwardly and having a downwardly extending tubular section at its inner edge fitting around said cap, the lower edge of said tubular section and the outer portion of the inclined guard plate itself resting upon the 115 top of the chimney proper.

3. A chimney top comprising a cap fitting the flue, a guard-plate extending outwardly from said cap and covering the top of the chimney proper, said plate being inclined 120 outwardly and downwardly and having a tubular section at its inner edge fitting around said cap, the lower edge of said tubular section and the outer portion of the inclined guard-plate itself resting upon the top of the 125 chimney proper.

4. A chimney top comprising a cap fitting the flue, and a guard-plate extending from

said cap in a continuous outward and downward incline to a point well beyond the outer surface of the chimney proper, the outer edge of said plate terminating beyond and being free from the outer surface of the chimney proper, and the inner edge of said plate terminating in a tubular section fitting around the cap for holding the plate rigidly in position, the lower edge of said tu-

bular section resting upon the top of the 10 chimney proper.

In testimony whereof I affix my signature in the presence of two witnesses.

FRANCIS W. FERGUSON.
